ELECTRIC STEAM VAPORIZER

William J. Russell, Kensington, Conn., assignor to Electric Steam Radiator Corporation, Paris, Ky., a corporation of Kentucky

Application June 6, 1958, Serial No. 51,229

Term of patent 3½ years

(Cl. D83—1)

FIG. 1

FIG. 2

Des. 187,171

PAGE 2

FIG. 3

FIG. 4

FIG. 5

FIG. 6

Fig. 1 is a top plan view of an electric steam vaporizer, showing my new design;

Fig. 2 is a side elevational view thereof;

Fig. 3 is a front elevational view thereof;

Fig. 4 is a rear elevational view thereof;

Fig. 5 is an enlarged perspective view thereof; and

Fig. 6 is an enlarged fragmentary section through the bottom ribs.

I claim:

The ornamental design for an electric steam vaporizer, as shown.
